UNITED STATES PATENT OFFICE.

THEODORE W. WASHBURN, OF BALDWINSVILLE, MASSACHUSETTS, ASSIGNOR
TO GILMAN WAITE, OF BALDWINSVILLE, MASSACHUSETTS, DOING BUSI-
NESS AS THE WAITE CHAIR COMPANY.

CONVERTIBLE CHAIR.

SPECIFICATION forming part of Letters Patent No. 708,278, dated September 2, 1902.

Application filed September 13, 1899. Serial No. 730,359. (No model.)

To all whom it may concern:

Be it known that I, THEODORE W. WASHBURN, of Baldwinsville, in the county of Worcester and State of Massachusetts, have
5 invented an Improved Convertible Chair, of which the following is a specification.

The object of my invention is to provide a convertible chair which is easily operated, which is of practical construction, and which
10 is readily locked in its raised position; and my invention is a convertible chair comprising a frame, a seat, crossed legs pivoted together, a link connection between the frame and front legs, a link connection between the
15 seat and front legs, and a spring-catch to lock the frame to the seat when the chair is in its elevated position.

In the accompanying drawings, Figure 1 is a side elevation of a convertible chair embodying my invention. Fig. 2 is a detail.

Seat A is provided with the usual back a and is mounted on crossed legs, of which B is one of the front pair, and B' one of the rear pair. These crossed legs are pivoted together
25 at b and are provided at their lower ends with wheels b'. Each rear leg B' is pivotally connected at b² to seat A, and each front leg B is connected to seat A by a link b³. Frame C is pivotally connected to each rear leg B'
30 at c and connected to each front leg B by links c'. Spring-catch D is rigidly secured to seat A and is slotted at d to receive member d', which is secured to round d² of frame C.
In Fig. 1 the chair is shown in its elevated po-

sition, and to lower it spring-catch D is raised, 35 member d' slipped by slot d, and the chair is then lowered by means of the frame, which through link c' controls the front legs and through pivot c controls the rear legs. From the lower position the chair is raised by the 40 frame and locked by the spring-catch.

It will be clear that my connection between the frame, the seat, and the legs enables me to confine the angular motion of the frame within small limits and also makes a firm 45 substantial support for the chair, whether used in its elevated or lowered position.

What I claim as my invention is—

1. In a convertible chair the combination of crossed legs pivoted together; a seat pivoted to the rear legs and connected by a link 50 to the front legs; and a frame pivoted to the rear legs and connected by a link to the front legs.

2. In a convertible chair the combination 55 of crossed legs pivoted together; a seat pivoted to the rear legs and connected by a link to the front legs; a frame pivoted to the rear legs and connected by a link to the front legs; and a spring-catch for holding the chair in its 60 elevated position, one member of the catch being on the frame and the other on the seat.

THEODORE W. WASHBURN.
